UNITED STATES PATENT OFFICE.

FRANK W. BAILER AND MAX WEINBERG, OF ST. LOUIS, MISSOURI.

CLOTHING-SEAM-PRESSING MACHINE.

Application filed October 21, 1920. Serial No. 418,427.

To all whom it may concern:

Be it known that we, FRANK W. BAILER and MAX WEINBERG, citizens of the United States, and residents of St. Louis, Missouri, have invented certain new and useful Improvements in a Clothing-Seam-Pressing Machine, of which the following is a specification.

This invention relates to improvements in a clothing seam pressing machine, and has for its object a mechanism which is conveniently placed on a table, the same provided with a pressing arm or table on which the garment is placed, a heated roller arranged to be placed on the seam, a seam spreader foot conveniently located for spreading the seam, driving rollers for advancing the garment under the heating roller and a means for raising the heating roller from the garment so that the same can be shifted on the arm or table.

The essential feature of our invention is to construct a machine having power driven driving rollers, an ironing roller which is properly heated by any means of heat supply, the same arranged to be raised and lowered for the advancing of the garment and a spreader foot whereby the seam is spread apart so as to be pressed flatly between the rollers.

Figure 1, is a side elevation of our invention with parts broken away and in section showing the general structure.

Fig. 2, is a front view of the same.

Fig. 3, is a central sectional view of the rollers made use of in carrying out our invention.

Fig. 4, is a cross sectional view of the same.

Fig. 5, is a detail perspective view of the spreader foot shown in application spreading a garment or seam.

Fig. 6, is a top plan view of our invention.

Fig. 7, is a detail front view of a cam mechanism made use of for raising and lowering the rear spreader foot.

Fig. 8, is a sectional view of the same.

Fig. 9, is a detail perspective view of a portion of the supporting arm, showing the leg or arm of a garment placed over the same in readiness for pressing the seam.

Referring to the drawings in detail 10 indicates the general frame of our invention the same consisting of a supporting body portion 11, the upper end thereof terminat-

ing into an extending arm 12 and attached 55 to the body portion 11 and at a convenient location beneath the arm 12 is a supporting arm or ironing table 13. These parts in the form of construction are generally formed integral. 60

On the arm 12 is formed a head 14 in which is supported a rod 15, on the lower end of which is supported a bifurcated roller support 16 in which is axially mounted a hollow roller 17. In the top of the head and around the rod 15 is placed a screw-threaded adjusting sleeve 18, the bottom end of which communicates with the upper end of a spring 19 located around the rod 15. The bottom end of the spring 19 is supported on the collar 20 attached to the rod 15 and the tendency of said spring is to normally hold the roller 17 in contact with the garment placed beneath the same. To the upper projecting end of the rod 15 is pivotally attached an operating arm 21, which straddles the rod 15 by means of its bifurcated end 22. This rod is supported on the arm 12 by a bifurcated support 23, the free end of the operating rod 21 being formed into an eye 75 24 to which is attached one end of a chain 25. This chain passes down through the hollow body portion 11, and its opposite end is attached to the foot lever 26, conveniently located on the floor and when the foot lever 70 80 is operated it will raise the rod 15 and the roller 17 sufficiently to permit a garment to be placed in position under the same.

On the head 14 is likewise supported a rod 27, on the bottom end of which is located a seam spreading head 28 with which the seam is first brought in contact and as the same is advanced forward under the roller it spreads the same from a vertical to a horizontal position as illustrated in Fig. 5. 95

This rod is supported in a bracket 29 attached to the front end of the head and around the rod and within the bracket is a spring 30 which rests upon a collar 31 attached to the rod and the tension of the 100 spring normally holds the foot 28 in contact with the table.

On this rod is attached a collar provided with a projection 32, this projection being located in alignment with a projection 33 105 formed on the bifurcated roller support and when the roller is raised upwardly this projection 33 contacts with the projection

32 and raises the spreader foot 28 away from the table.

In order to obtain additional pressure upon the foot 28 we provide a foot operating mechanism which consists of a lever 34 pivotally attached to the bracket 35 formed on the head 14, said bracket loosely contacting with the upper portion of the rod 27. Its opposite free end is connected to the rod 36 which extends downwardly and is attached to a foot lever 37, and by pressing downwardly on the lever with the foot it pulls down on the rod and additional pressure can be obtained.

15 To the rear of the head 14 is likewise located a rod 38, and around this rod is also placed a spring 39 the tension of which normally holds the foot 40 of this rod in contact with the table, and in order to hold this foot in elevated position as shown by solid lines in Fig. 1, we provide a cam mechanism 41, the same being attached to the frame of the head by means of a cap screw 42, said cam mechanism being provided with a cam slot 43, in which projects a pin 44 extending from the rod 38, and when the cam is in horizontal position as shown in Fig. 7, the foot is down and when the operating handle 45 of the cam is pressed down and in 20 a vertical position it brings the pin 44 to its highest position thereby raising the foot 40 and is held in such position until the cam is again released from the vertical to a horizontal position.

35 In the arm or ironing table 13 is located a shaft 46. This shaft is supported in suitable bearings 47, and on the same is located a drive sheave 48 over which a belt 49 is placed and said belt may be attached to 40 any sort of power supply as a shaft as indicated by the numeral 50 or to the ordinary driving mechanism or said shaft may be driven direct from the motor, if so desired.

45 On this shaft 46 is placed a pair of worms 51 which are arranged in mesh with worm gears 52 mounted in trunnions 53 formed on driving rollers 54, which are preferably two in number, the periphery of said rollers 50 operating through openings formed in the upper surface of the ironing table and are arranged to project slightly above the surface thereof and said rollers are so positioned as to permit the heating roller to 55 contact with both of said rollers, these rollers by means of the worm mechanism being driven in the same direction.

The hollow heating or ironing roller 17 is supported in the bifurcated supporting frame 16 by sleeves 55 and in these sleeves is supported a pipe 56 which is provided with a plurality of small holes 57, through which gas may pass and when ignited will form small flames for heating said roller. 60 The gas is admitted to the pipe through a

flexible connection 58. If found desirable this roller may be heated by steam or electricity as found most applicable.

The operation of our invention is as follows:

In the construction of clothing after the legs, sleeves and sections of the garment are stitched together and when the same is formed there are projecting ends which normally project outwardly. In order that these edges may be flattened down to form a flat seam the garment is placed on the ironing table and in the event of a sleeve or trouser leg it is slipped over the table. The operator exerting pressure on the foot lever 26 raises the ironing roller together with the presser foot; when so raised, the garment is placed on the table 13 and when pressure is released the roller and foot will contact with the garment, the foot forming the seam as indicated in Fig. 5, flattening down the edges, the rollers have a tendency to advance the garment beneath the heating roller. When the entire seam has passed under the roller and is ironed flat the operator then elevates the roller and presser foot, then turns the garment to bring the next or opposite seam between the rollers, this operation being accomplished while the garment is on the table, then the mechanism is reversed and the inner presser foot lowered so as to flatten out the seam and when drawing the same off of the table the roller will perform its ironing function. In Fig. 9, we show an illustration of the 100 table with the garment leg or arm in position on the same.

Having fully described our invention what we claim is:

1. A clothing seam pressing machine 105 comprising a frame, a stationary overhanging head, a garment supporting arm formed integral with and extending from the frame, rollers supported in said arm, and a heated ironing roller located above the arm and supported in the overhanging head to contact with a garment for ironing out the seam, substantially as specified.

2. A machine of the character described comprising a frame, a garment supporting arm projecting therefrom, rollers mounted in said arm, a mechanism imparting motion to said rollers, a stationary overhanging head, an ironing roller supported in said head above the arm, means for raising and lowering said ironing roller, and a presser foot on each side of the ironing roller for opening the seam prior to admitting the garment between the rollers, substantially as specified.

3. A machine of the character described comprising a frame, having a supporting over-hanging head, an arm projecting from the frame and in alignment with the over-hanging head, a pair of power driven

rollers located in the arm, a spring compressed heated ironing roller supported in the over-hanging head and arranged to contact with the periphery of both driving rollers, means for controlling the pressure of the ironing roller, a presser foot located in the front and to the rear of said roller, and means for regulating the pressure of the feet on the garment, substantially as specified.

4. A machine of the character described comprising a frame, the upper end terminating into an arm, a head formed on the end of said arm, a spring actuated rod located in said head, an ironing roller supported by the lower end of said rod, a heat generator located in said roller, an operating lever connected to said rod by which the same may be raised and lowered, an arm projecting from the frame on which the garment to be pressed is placed and power driven rollers located in the arm on which the garment is supported during the ironing process, substantially as specified.

5. A machine of the character described comprising a frame, an arm forming a part thereof, said arm acting as an ironing table around which the garment to be pressed is placed, a rotatable heating mechanism supported by the frame and permitted to contact with the garment for pressing and flattening the seam of the garment without making an imprint on the remainder of the garment, substantially as specified.

6. A clothing seam pressing machine comprising a frame constituting an integral upper arm provided with an overhanging head; a garment supporting arm formed integral with and extending from

the frame; a shaft supported in said arm; worms mounted on said shaft; a pair of rollers located in the arm in mesh with the worms on said shaft; the periphery of said rollers projecting slightly through the top 45 of said arm; a rod vertically mounted in the overhanging head; an ironing roller supported by said rod; a spring mechanism for normally holding the ironing roller against the periphery of two lower rollers; 50 a lever mechanism communicating with the vertical rod by the manipulation of which the ironing roller may be raised out of contact with the lower rollers; a presser foot positioned on each side of the ironing roller and supported by the overhanging head, said foot designed to spread the seam and flatten out the same before entering the three rollers, the garment supporting arm being so arranged as to permit the leg of a 55 trouser or a sleeve of a coat to pass thereover, substantially as specified.

7. A clothing seam pressing machine comprising a head having two horizontal portions, the lower horizontal portion being 60 free and unobstructed so that a completely sewed garment may be inserted thereover, rollers mounted in said horizontal portions, means for heating at least one of said rollers, and means for placing said rollers in 65 operation simultaneously.

In testimony whereof, we have signed our names to this specification, in presence of two subscribing witnesses.

FRANK W. BAILER.
MAX WEINBERG.
